UNITED STATES PATENT OFFICE.

ALBERT M. SPAULDING, OF FLOWERFIELD, MICHIGAN, AND HERBERT L. CASE, OF BRISTOL CENTRE, NEW YORK.

WRENCH.

SPECIFICATION forming part of Letters Patent No. 390,408, dated October 2, 1888.

Application filed January 6, 1888. Serial No. 259,935. (No model.)

To all whom it may concern:

Be it known that we, ALBERT M. SPAULDING, of Flowerfield township, in the county of St. Joseph and State of Michigan, and HERBERT L. CASE, of Bristol Centre, in the county of Ontario and State of New York, have invented a new and Improved Vehicle-Wrench, of which the following is a full, clear, and exact description.

10 The object of our invention is to provide a new and improved wrench specially adapted for conveniently unscrewing the nuts of vehicle-axles for removing the wheels for lubricating or for other purposes.

15 The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

20 Figure 1 is a side elevation of the improvement as applied. Fig. 2 is a sectional plan view of the same on the line $x-x$ of Fig. 1. Fig. 3 is a sectional end elevation of the same on the line $y-y$ of Fig. 1, and Fig. 4 is an enlarged sectional plan view of the jaws and bent bar.

25 The improved wrench A is provided with the jaws B and C, of which the jaw B is adapted to be secured to a bent bar, D, by means of a set-screw, B', screwing in the said jaw B and against the spring-bar D, which passes through the said jaw B. The other jaw, C, is held to

30 slide loosely on the spring-bar D, and the two jaws B and C are adjusted toward or from each other on the bent bar D by means of a screw-rod, E, screwing into the loosely-sliding jaw C and extending at its smooth end F into the jaw B, as shown in Fig. 4. In this part F of the screw E is formed an annular groove, G, into which projects a set-screw, H, screwing into the top of the jaw B. This arrangement

35 permits of turning the screw-rod E in the jaw B and prevents it from falling out of the same. Screw-rod E is provided with a milled collar, I, for turning the said screw-rod E, located, preferably, between the two jaws B and C, as

40 shown. The bar D is bent so as to extend at

its middle in front of the hub of the vehicle-wheel and at its ends between the spokes.

On the ends of the bent bar D are held to slide the arms J and J', extending at right angles to the said bent bar D, and each provided at each end with a recess, K, adapted to fit the inner sides of two successive spokes, L, of the vehicle-wheel N, held in place on the axle O by the nut P, on which the said wrench A is to operate. To the middle of the arm J' 55 is secured one end of a coiled spring, Q, fastened by its other end on the arm J and serving to pull the arm J' inward tightly on the respective spokes L.

The operation is as follows: When it is desirable to remove the nut P from the axle O, so as to be enabled to take off the wheel N, the operator adjusts the jaws C and B to the size of the nut P by turning the milled collar I, so that the screw-rod E moves the jaw C, according to the size of the nut P, toward or from the jaw B, fixed on the bent bar D. The operator then inserts the arm J' between two spokes, L, and pulls the bar D until the jaws B and C fit onto the nut P. The operator then 60 bends the other end of the bar D between the spokes and slides the other arm, J, inwardly until it engages the two successive spokes, L, as shown in Figs. 1 and 2. When the operator 65 now turns the wheel N, the wrench A turns 70 with it and unscrews the nut P from the axle O. As soon as the nut P is unscrewed from the axle O the operator can remove the wheel N for lubricating or other purposes.

When the operator desires to place the wheel 75 N on the axle O again, he places the said wheel on the spindle of the axle and turns it several times, so that the nut P, which is securely held by the jaws B and C of the wrench A, is again 80 screwed on the threaded end of the axle O. As soon as the nut P is adjusted as described the operator slides the arm J outward until it is 85 disengaged from the spokes, and the wrench A can now be easily taken off the wheel N. Thus it will be seen that the nut is easily taken off 90 or put on the threaded end of the axle O without being touched by the operator.

Having thus fully described our invention, we claim as new and desire to secure by Letters Patent—

1. A vehicle-wrench comprising a bar having a wrench-head between its ends and arms mounted adjustably between their ends on the bar at opposite sides of the wrench-head and 5 at right angles thereto, the opposite ends of each arm being adapted to engage a spoke, substantially as set forth. wrench-head on the bar between its ends, arms sliding between their ends on said bar at opposite sides of the wrench-head and at right angles thereto, and a spring secured to the bar 25 and to one end of said arms and drawing it toward the wrench-head, substantially as set forth.
2. A vehicle-wrench comprising a bar arched between its ends, a wrench-head on said arched 10 portion and projecting inward between the sides thereof, and sliding arms mounted between their ends on the bar at opposite sides of the arch and at right angles to the wrench-head, substantially as set forth. 5. A vehicle-wrench comprising the arched bar, adjustable nut-receiving jaws on said 30 arched portion, arms mounted between their ends on said bar at right angles to said jaws and recessed at both ends to engage the adjacent sides of two spokes, and a spring drawing one arm toward the said jaws, substantially 35 as set forth.
- 15 3. A vehicle-wrench comprising a spring-bar arched between its ends, adjustable jaws sliding on the arched part of the bar, and arms mounted between their ends on the bar at opposite sides of the arch and at right angles to the said jaws, substantially as set forth. 20 4. A vehicle-wrench comprising a bar, a
